(57) **CLAIM**

The ornamental design for an indoor plant cultivator, as shown and described.

DESCRIPTION

FIG. 1 is a front perspective view of the indoor plant cultivator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view of the indoor plant cultivator shown in an environment of use with a broken line seed kit; and.

FIG. 9 is an exploded perspective view with the water tank separated and showing the environmental structure of a seed kit.

The broken lines depict portions of the Indoor plant cultivator that form no part of the claimed design. The dash-dot broken lines define the boundary of the claimed design and form no part thereof. The broken lines in FIGS. 8 and 9 showing a seed kit show environmental structure only and form no part of the claimed design.
